UNITED STATES PATENT OFFICE.

FRANK NATHER, OF JOHNSTOWN, PENNSYLVANIA, ASSIGNOR TO THE LORAIN STEEL COMPANY, A CORPORATION OF PENNSYLVANIA.

STEEL CASTING.

SPECIFICATION forming part of Letters Patent No. 789,289, dated May 9, 1905.

Application filed January 2, 1904. Serial No. 187,571.

To all whom it may concern:

Be it known that I, FRANK NATHER, of Johnstown, in the county of Cambria and State of Pennsylvania, have invented a new and useful Improvement in Steel Castings, of which the following is a full, clear, and exact description, reference being had to the accompanying drawings, which form a part of this specification.

My invention has reference to steel castings, and more particularly to castings designed for use in railway-track construction, and is designed to free the casting from internal strains due to inequality of section. Considerable trouble has been experienced, particularly where special steels are used, to produce a perfect integral steel casting for use in trackwork, owing to the difficulty of distributing the metal in those portions of the structure where the rail members or extensions meet in such a manner as to avoid the junction of parts of unequal section. Where such junctions occur, the fact that the thinner portion of metal will cool more rapidly than the thicker portions, both in the mold and in subsequent heat treatment, gives rise to internal strains which spoil or weaken the casting. By the present invention I avoid this result by so disposing the metal that the junction of parts of unequal thickness is obviated and a casting is formed which is of substantially equal section throughout.

My invention will be better understood by reference to the accompanying drawings, in which—

Figure 1 is a plan view of a track-structure casting embodying my invention; Figs. 2 and 3, similar views of portions of different structures; Fig. 4, a section on the line 4-4 of Fig. 1; Fig. 5, a section on the line 5-5 of Fig. 3; Fig. 6, a plan view of a modified form of structure; Fig. 7, a section on the line 7-7 of Fig. 6, and Fig. 8 a plan view of a more complicated structure embodying the invention.

Figs. 1 to 5, inclusive, illustrate my invention as applied to track structures of the type which employ a removable plate or center, which forms the track intersections. The

letters A' A² A³ A⁴ designate the rail members of the structure, having the head portions a, the webs a', and the base portions a². B designates the central connecting portion of the castings, formed with the plate-receiving core or pocket b. The central portions B of the castings have been those portions of the castings which have presented the difficulty above noted owing to the junction of the several web portions a' into a common central body. This I avoid by keeping said web portions separate and independent of each other—that is to say, the web portions of the rail members A' A² are carried continuously through the structure, as are also the said portions of the members A² A³, the two web portions at the central portion of the structure being substantially parallel with each other. This enables me to so dispose the metal that the casting has a substantially equal thickness or section throughout, as will be seen from Figs. 4 and 5. It is desirable that these web portions shall be thicker than the section of an ordinary rail-web, not only to give increased strength to the structure, but also to make their section approximately equal to that of the portions A and B. Therefore, at the point c in each of the rail members said portions a' are gradually thickened, as shown. Beyond the points c said webs are preferably of the same thickness as the web of the connecting track-rails in which the structure is to be connected, so that the usual fish-plates can be employed in making the joints.

Figs. 6 and 7 show the invention applied to a structure which does not employ an intersection plate or center.

Fig. 8 shows the invention applied to a crossing structure in which a double rail is crossed by a single rail. The thin web portions a³, a⁴, and a⁵ are carried continuously through the central portion B' of the structure, the continuous web a³ being common to the rail members A⁴ and A⁵, the web portion a⁴ to the rail members A⁶ and A⁷, and the web A⁵ common to the rail members A⁸ and A⁹.

My invention is obviously applicable to many other specific forms of track structures,

in all of which it is to be broadly distinguished by the fact that the rail members and the central portion are at all points in and adjacent to the central portion of substantially uniform thickness, and the structure is free from the junction of relatively thicker and thinner portions. Hence I do not wish to be limited to the particular structures which I have here shown for the purpose of illustrating my invention.

Having thus described my invention, what I claim as new, and desire to secure by Letters Patent, is—

1. A railway-track-structure casting, consisting of diverging rail-member portions, and a central connecting portion, the metal in said rail portions and in the said central portion being of substantially uniform thickness, whereby the central part of the structure is free from junctions of relatively thicker and thinner sections of metal.

2. A railway-track-structure casting, consisting of diverging rail-member portions, and a central pocketed body portion, the metal in said rail portions and in the central pocketed portion being of substantially uniform thickness, and the central part of the structure free from the junction of relatively thicker and thinner portions.

3. A railway-track-structure casting, consisting of a central connecting portion and diverging rail-member portions, said rail-member portions being connected in pairs by webs extending continuously through the central portion.

4. A railway-track-structure casting, consisting of a central connecting portion and diverging rail-member portions, said rail-member portions being connected by continuous independent webs which extend through and support said central portion.

5. A railway-track-structure casting, consisting of a central connecting portion and diverging rail-member portions, united by continuous independent webs which extend

through said central portion in substantially parallel relation.

6. A railway-track-structure casting consisting of a central connecting portion and diverging rail-member portions connected by webs extending through and supporting said body portion, said rail members, webs and body portion being of substantially uniform thickness or section.

7. A railway-track-structure casting, having diverging rail members and a central connecting portion supported by web portions each of which is continuous with the webs of two of the rail members.

8. A railway-track-structure casting, having diverging rail members and a central connecting portion supported by web portions each of which is continuous with and connects the webs of two of said rail members, said parts being all of substantially uniform thickness or section and free from junctions of parts of unequal thickness.

9. A railway-track-structure casting, consisting of a central connecting portion and integral diverging rail members, said connecting portion and rail members being of substantially uniform thickness throughout except at the end portion of the rail members where the web portions thereof are reduced to approximately the thickness of the web portion of a rolled rail.

10. A railway-track-structure casting having two or more continuous webs extending the full length of the structure and having each an independent base or foot.

11. A railway-track-structure casting having two or more continuous independent webs extending the full length of the structure and of reduced thickness at their end portions.

In testimony whereof I have affixed my signature in presence of two witnesses.

FRANK NATHER.
